UNITED STATES PATENT OFFICE

156,558

KITCHEN STOVE VENTILATOR

William A. Pledger, San Francisco, Calif.

Application August 28, 1948, Serial No. 148,354

Term of patent 14 years

(Cl. D81—25)

To all whom it may concern:

Be it known that I, William A. Pledger, a citizen of the United States, residing at 67 Melrose Avenue, San Francisco, California, have invented a new, original, and ornamental Design for a Kitchen Stove Ventilator, of which the following is a specification, reference being had to the accompanying drawing, forming part thereof, in which:

Fig. 1 is a perspective view of a kitchen stove ventilator showing my new design.

Fig. 2 is a side view thereof; and

Fig. 3 is a reduced back view thereof.

I claim:

The ornamental design for a kitchen stove ventilator, as shown.

WILLIAM A. PLEDGER.
